UNITED STATES PATENT OFFICE

2,631,030

BOLSTER BUMPER

Alfred O. Williams, Battle Creek, Mich., assignor
to Clark Equipment Company, Buchanan,
Mich., a corporation of Michigan

Application May 8, 1947, Serial No. 746,701

2 Claims. (Cl. 267—3)

1

This invention relates to rail car trucks and more particularly is directed to an improved type of rail car truck for use on surface lines, subway and elevated lines in metropolitan areas.

The present invention is broadly concerned with a truck construction of the type described in detail in my co-pending application, Serial No. 721,993, filed January 14, 1947, now abandoned.

The truck with which my present invention is embodied includes a bolster having a non-metallic cushioned support to allow lateral and longitudinal movement thereof relative to the side frame members of the truck. The support consists of a vertical pile of rubber sandwiches operating in compression to carry the load of the bolster onto the side frame of the truck, together with laterally disposed sandwiches acting in shear and supplementing the load carrying support of the vertical pile of sandwiches, but also providing for cushioned support against oscillation of the bolster longitudinally and laterally of the truck.

A primary object of my present invention is to provide a non-metallic restraining member, having a varying rate of deflection, interposed between the bolster and the inner side of the side frame member, which comes into play whenever the bolster tends to oscillate laterally relative to the truck, serving as a cushioning and dampening member for restraining such oscillation, thereby increasing the resistance of such oscillation gradually, rather than interrupting this motion suddenly.

In addition, the present invention has, for another object, the provision of the lateral cushioning members which not only supplement the vertical rubber members for supporting a portion of the body load, but give a more rapid build-up of resistance to longitudinal oscillation of the bolster relative to the truck.

Other objects and advantages of the present invention will appear more fully from the following detailed description, which, taken in conjunction with the accompanying drawings, will disclose to those skilled in the art, the particular construction and operation of a preferred form of the present invention.

In the drawings:

2

Figure 1 is a top plan view of a rail truck embodying the present invention.

Figure 2 is a detailed side elevational view at the bolster support with portions broken away for purposes of clarity.

Figure 3 is a sectional view taken substantially on line 3—3 of Figure 2.

Figure 4 is a side elevational view of the bumper mechanism shown in Figure 2.

Figure 5 is a top plan view of the bumper member shown in Figure 2.

Referring now in detail to the drawings, the truck consists generally of the top side frame members, indicated at 5, which extend in par-

5 alallel relationship and are provided with depending post portions 6, spaced on opposite sides of transverse axle housings 7. The axle housings 7 may be of the type shown generally in the co-pending application of Robert J. Burrows and

20 Alfred O. Williams, Serial No. 567,618, filed December 11, 1944, and issued on October 29, 1946, as Patent No. 2,410,011, and enclose a solid axle shaft which projects beyond the ends of the

25 housings and has pressed thereon, resilient car wheels 8. The wheels 8 are preferably of the type wherein the tread member or rim is re-

siliently supported by rubber sandwiches upon a flanged hub member.

Intermediate the ends of the axle shaft upon

30 which the wheels are mounted, there is provided a bevel gear drive, adapted to be enclosed within the enlarged portion 9 of the axle housings and to be driven by the shaft 10 carrying a driving pinion extending into the nose portion 12 of the

35 housings 9 and connected, in turn, through a suitable universal joint connection, to the drive shaft 13, which extends from the electric driving motors 14. It will be noted that the two

40 motors carried by the truck are positioned in laterally offset and longitudinally spaced position relative to the truck, and face in opposite directions.

The motors 14 are adapted to be supported in

45 the cradle portions 15 of transverse frame members 16, which extend crosswise between the side frame elements, and are provided with suitable

50 pad portions 17, whereby they are welded to the under surface of the side members 5. The transverse members 16 are also provided with

openings 18, through which the drive shaft 13 of the opposed motors are adapted to extend. The cradle portion 15 of these members is adapted to receive a cap member 19, bolted thereon, which firmly supports the motors in fixed position on the transverse members.

Preferably, there is provided a motor shaft brake, indicated generally at 20, which, through the actuating rod 22, extending laterally outwardly beneath the frame members 5, is adapted to provide braking action for the truck and which may be actuated either by air pressure or by electrical controls in a well known manner.

The transverse bolster member 25, which extends between the side frames of the truck intermediate the cross members 16, has provided therein the king pin opening 26 for receiving the king pin of a car body, and has oppositely extending end portions 28 which project laterally beneath the side frame members 5. These side frame members 5 are provided on opposite sides of the extending ends 28 of the bolster with downwardly depending parallel spaced plates 29 which may be welded or otherwise suitably secured to the side frame members, as indicated at 29', and which terminate at their lower ends by being welded to depending bracket members 30, which bracket members have the ends thereof bent upwardly and secured to the frame at the point where the transverse frame members 16 are secured to the side frame members 5.

Mounted on the members or brackets 30 intermediate the plates 29, is a vertically extended multiple stack of horizontally disposed rubber sandwiches, indicated generally at 33, these sandwiches having metal plates vulcanized to opposite faces thereof, with the lowermost plate 31 being bolted to the bracket member as by means of the bolts 33'. The extending ends 28 of the bolster member 25, are preferably of inverted channel shape, as indicated at 34, and are provided with suitable bolt means for fastening the upper plate 35 of the spring assembly to the under face of the web portion of the bolster end 34, as by means of bolts extending through the bolt holes, indicated in dotted lines in Figure 2.

The ends 28 of the bolster 25 are provided adjacent the inboard edges of the plates 29, with boss portions 36, upon which is disposed a flat plate member 37, supporting the flanged end 38 of a bracket 39, the opposite end of the bracket 39 being supported upon the boss 40 of the curved portion of the bolster and being secured thereto by means of the stud bolt 42. The bolts 43 are adapted to extend through the web portion 34 of the end 28 of the bolster, through the boss 36 and the plate 37 and then through the flanged end 38 of the bracket 39 for securing this bracket rigidly to the end of the bolster 25. Two of such bolts are indicated at 43 in Figure 2, and the other two bolts, which are disposed on opposite sides of the bolts 43, extend through the dotted line openings for securing the upper end of the cushioning member 35 to the end of the bolster.

The side flanges of the channel shaped end 34 of the bolster, indicated at 44, have machined outer surfaces, adapted to be engaged by the plate members 45 of a rubber sandwich 46, which plate members have extending ear portions bolted to the side flanges 44, as by means of the bolts 47. The opposite plates of the sandwich 46 are secured to the facing surfaces of

the depending plates 29 as by means of bolts 48, thereby positioning the sandwiches 46 between the side flanges of the bolster end and the plates 29 fixed on the side frame. Thus the cushioning members 46 are placed in vertical shear to support a portion of the load of the bolster, the main portion of which is carried by the compression of the stack of cushioning members 33.

Mounted on the vertical face of the brackets 39, there is provided rubber bumper members 50, which members include a rubber body element 52, as shown in Figures 4 and 5 of varying cross section and preferably provided with perforations 53 and 54 to give this member a non-uniform rate of compression, and, in effect, an increasing rate of compression per unit of load. The rubber member 52 is vulcanized at its base to a plate member 54', carrying the stud 55 by which the same may be secured to the bracket 39. The configuration of the bumper members 50, wherein the forward end has a gradually reducing rounded portion and the transverse openings 53 and 54 formed therethrough decrease in diameter from the rounded end to the metallic base, is such that an increasing rate of resistance per unit of load is offered by the bumper members 50. It will be noticed that the forward end of the bumper 50 is disposed adjacent the inner lateral surface of the side frame member 5, so that upon lateral movement of the bolster 25, relative the truck, the bumper will come in contact with this side face and serve to cushion or restrain, by gradually increasing increment, the lateral movement of the bolster.

The remaining details of the truck construction are substantially the same as shown in my co-pending application referred to above, and hence, it is not believed necessary to describe them further.

It will be apparent that with the present construction, there is provided a bolster support on the side frame elements of the truck, whereby the bolster member is cushioned by non-metallic means with respect to vertical loads, but is arranged to have limited vertical and lateral movement. The vertical load is taken by the conjoint action of elements 33 and 46, the elements 46, in this case, acting in shear. The elements 46 also act in shear in combination with shear action on the elements 33 to restrain lateral movement of the bolster and the bumpers 50, providing a gradually increasing increment of resistance to such lateral movement.

I am aware that various changes may be made in certain details of the construction herein disclosed, and therefore, I do not intend to be limited except as defined by the scope and spirit of the appended claims.

I claim:

1. A bumper for the bolster of a rail car truck to cushion transverse oscillations thereof relative to the side frame members of said truck comprising a nonmetallic resilient cylindrical body member having a gradually reducing rounded end, and seated on a flat metallic base, said member having a plurality of transverse holes formed therethrough decreasing in diameter from said rounded end to said metallic base.

2. A bumper for the bolster of a rail car truck to cushion transverse oscillations thereof relative to the side frame members of said truck comprising a nonmetallic resilient block member seated on a flat metallic base, and said mem-

ber having a plurality of transverse holes formed therethrough increasing in diameter from said metallic base to the outer end thereof.

ALFRED O. WILLIAMS.
